United States Patent Office

Des. 205,251
Patented July 12, 1966

205,251

CONTINUOUS PHOTOGRAPHIC FILM PROCESSING APPARATUS

Philip E. Hixon, 156 Willowwood Drive, Wantagh, Long
Island, N.Y., and Marvin B. Fleisher, 14 High Top Lane,
Jericho, Long Island, N.Y.

Filed Mar. 25, 1965, Ser. No. 84,443

Term of patent 3½ years

(Cl. D61—1)

FIG.4

FIG.3

FIG.2

FIGURE 1 is a front perspective view of a continuous photographic film processing apparatus showing our new design;

FIGURE 2 is a right-side elevational view thereof, on a reduced scale;

FIGURE 3 is a rear elevational view thereof, and

FIGURE 4 is a left-side elevational view thereof.

We claim:

The ornamental design for a continuous photographic film processing apparatus, as shown.
